UNITED STATES PATENT OFFICE.

WILLIAM E. COOK, OF NEW YORK, N. Y., ASSIGNEE, BY MESNE ASSIGNMENTS, TO THE PEERLESS INSULATED WIRE AND CABLE COMPANY, OF NEW YORK, N. Y., A CORPORATION OF DELAWARE.

WIRE-COVERING MACHINE.

Application filed December 13, 1918. Serial No. 266,565.

To all whom it may concern:

Be it known that I, WILLIAM E. COOK, a subject of the King of the United Kingdom of Great Britain and Ireland, residing at 5 St. George, in the borough of Richmond, city of New York, county of Richmond, and State of New York, have invented certain new and useful Improvements in Wire-Covering Machines, of which the following 10 is a specification, reference being had therein to the accompanying drawings, which form a part thereof.

My invention relates to wire covering machines, and more particularly to a machine 15 adapted to apply an insulating base composed of cotton sliver, or other similar absorbent material, to a conductor wire.

With machines of the character to which my invention relates, great difficulty has 20 heretofore been experienced in applying adhesive to the conductor wire for the purpose of securing the desired bond between the sliver and the wire, particularly when it is desired to operate the machine at high 25 speeds.

Ordinarily it has been the practice to pass the wire through a bath of the adhesive, but at the higher speeds, there is a tendency of 30 the wire to pick up an excess quantity of the adhesive, thus causing it to be present on the wire, at the point of application of the sliver, in sufficient volume to prevent that partial setting of the adhesive necessary to make it sufficiently tacky to adhere 35 to the fibers of the sliver, the fluid condition of the adhesive at this point resulting not only in a failure of the sliver to properly bond to the wire, but in the absorption by the sliver of a sufficient quantity of the 40 adhesive to prevent the subsequent thorough saturation or impregnation of the sliver with asphaltum, or other composition, for weather-proofing and increasing the insulating properties thereof.

My present invention is adapted to permit 45 the utilization of a cold adhesive in a machine of this character, the structure being such as to ensure a continuous feed of adhesive in relation to, and its application to, 50 the wire, in sufficiently small volume to ensure the presence of only a thin film of adhesive thereupon. The flow of the adhesive with relation to the wire is automatically

controlled in a manner to ensure substantial uniformity in the volume thereof applied to the wire. The adhesive feeding mechanism is so constructed as to permit the interruption of the flow of adhesive therefrom, when the machine is stopped. 55

I also incorporate in a machine made in 60 accordance with my invention, an automatic stop mechanism, operative when the supply of sliver in the barrels is exhausted, thus preventing over-running of the machine under these conditions. 65

The invention consists in the novel features of construction and combination of parts, hereinafter set forth and described, and more particularly pointed out in the 70 claims hereto appended.

In the accompanying drawings, I have shown a front view of a machine embodying my invention, said view being partly in elevation and partly in section.

In the embodiment of my invention shown 75 in the drawings, 1 indicates the side frames of the machine, said frames being connected adjacent the bottom and the top thereof with cross frames 2 and 3.

Rotatably mounted within the side frames 80 of the machine, and above the cross frame 2, is a rotating platform 4 adapted to receive one, or a plurality of barrels 5, having coiled therein the cotton sliver, or other absorbent material with which the wire is to 85 be covered.

The platform 4 is provided with a hollow arbor 6 mounted in a suitable bearing in the cross frame 2. Supported from the platform by means of suitable standards 7, is a 90 top frame 8 carrying a hollow arbor 9 mounted in a suitable bearing in the upper cross frame 3. The edge of the platform 4 is inclined as shown, so as to pitch the barrels 5 inwardly of the platform, toward 95 its axis of rotation, and thus prevent centrifugal action acting upon the sliver in a manner to cause it to be entangled within, or as it is being withdrawn from, the barrels. 100

The arbor 9 projects above the cross frame 3, and is surmounted by a compacting die 10. The top frame 8 also carries a preliminary compacting die 11. Mounted upon a shaft 12, above the top frame 3, is a wire 105 feed sheave 13.

In the accompanying drawings, I have indicated the conductor wire at 14, said wire passing about the guide pulley 15 adjacent the bottom of the machine, for securing the 5 desired alinement thereof with the arbors 6 and 9, and the dies 10 and 11. The strip of sliver for covering the wire is indicated at 16.

Adjacent the die 10, the arbor 9 has 10 loosely mounted thereon a rotating table 17 having a plurality of spindles 18 thereon, adapted to receive spools of binding strands or threads. This table receives rotary movement from the arbor 9 through the gear train 19, the first of which gears is carried by said arbor, and the last of which gears is carried by said table, the intermediate gears being mounted upon the cross frame 3. The 15 layout of this gear train may be such as to 20 rotate the table in the same direction as, or in an opposite direction to, the direction of rotation of the arbor 9, and at the same, or a greater or less speed, according to the direction and the angle of inclination at which 25 it is desired to apply the binding strands or threads to the covered wire. The table 17 carries a flanged plate 20 having eyes therein through which the strands or threads pass from the spool to their point of application 30 to the sliver-covered wire, an ordinary tension device, as 21, being disposed between said plate and the spindles 18.

To ensure the application of said strands or threads to the covered wire, before the 35 sliver has had an opportunity to expand after leaving the die 10, I form the outlet end of said die as a truncated cone, the top of which is brought down to a narrow edge.

To prevent the toppling of the barrels 5 as a result of the action of centrifugal force thereon, I provide supporting straps 22 adapted to engage said barrels toward the top thereof, said straps being carried by the standards 7.

45 After leaving the sheave 13, the covered and bound wire is wound upon a reel, not shown, the laying of succeeding convolutions of the wire upon said reel being controlled by an ordinary traverse device indicated at 50 23.

Power for actuating the various mechanisms of the machine, is derived from the main shaft 24, said shaft having splined thereon the first gear, 25, of a gear train 26, 55 the last gear of which is carried by the arbor 6. Said shaft 24 is also connected by the reducing chain and sprocket mechanism 27, with the shaft 12, and power is transmitted from said shaft 12 by means of a pulley 28 thereon, to a pulley 29 carried by a shaft carrying a gear 30 connected by means of the chain and sprocket mechanism 31 with the traverse mechanism 23, and through the 60 gear 32 with the shaft 33 upon which the 65 rewind reel is mounted.

The shaft 24 has loosely mounted thereon a pulley 34, which is adapted to be connected to said shaft by means of the clutch 35.

To control the application of power to the shaft 24 through the clutch 35, I provide 70 means whereby said shaft may receive axial movement, as the hand lever 36. I also utilize this hand lever for applying brakes to the platform 4, so as to check rotation of said platform substantially simultaneously 75 with the disconnection of the clutch 35. This brake mechanism comprises the slides 37, oppositely mounted with relation to said platform, one end of each of said slides being provided with suitable brake shoes 80 adapted to engage the edge of said platform, and a lever acting upon each of said levers being connected by the rod 38, provided with a turnbuckle 39, for adjusting the position of these slides with relation to said platform. One of the slides 37 is connected by the link mechanism 40 to the hand lever 36, so that the movement of said lever 36 to release the clutch, will set said brakes, and the movement of said lever in the opposite 85 direction, to set said clutch, will release said brakes.

The mechanisms heretofore described relate to a high speed covering machine invented by me, but it is not my intention in 95 the present application to claim same specifically.

Other characteristics of the machine to which I will now refer, have particular application to a high speed machine of this 100 type, however, and the foregoing description is entered into, and the showing of such a machine is made in the drawings, in order that there may be a clear understanding of the invention.

105 Before the wire 14 reaches the point of application of the sliver, or other material, thereto, it is essential that the wire be coated with adhesive, to facilitate the application of the sliver, or other material, thereto, and form a permanent bond between the same and the wire. When a machine is operated at high speed, if the wire be passed through a bath of the adhesive, even though the adhesive be cold, there will be a tendency of the wire to accumulate the adhesive in a quantity in excess of that required, so that when the wire reaches the point of application of the sliver, or other material, thereto, the adhesive will remain upon same in sufficient volume, and be sufficiently fluid to not only prevent the proper bonding of the sliver, or other material, thereto, but to cause said sliver, which is highly absorbent, to absorb a sufficient quantity of the adhesive to prevent the proper saturation or impregnation of the sliver, or other material, with the asphaltum or other composition with which it is subsequently treated. To avoid this condition, I provide means where- 115 120 125 130

by a thin, substantially uniform, film of adhesive will be applied entirely about the wire, while it is passing through the machine, the wire not being in contact with a sufficient volume of adhesive to permit of its accumulation thereon in a quantity in excess of that required. In this manner, although the rate of travel of the wire be fairly rapid, the adhesive will have had opportunity to partially set, so that when it reaches the point of application of the adhesive thereto, it will be merely tacky, and thus secure the desired bond, without a substantial or material saturation of the sliver, or other material, therewith.

In the form of the invention shown, I provide a tank 41 having a well surrounding a tubular portion 42, the opening in this tubular portion being axially alined with the arbor 6, and having an inturned top with an opening therethrough, slightly greater than the diameter of the wire. The tank 41 is in connection through a flexible tube 43, with a reservoir 44, the top of which has an opening therethrough, adapted to receive the neck of a carboy 45 containing a quantity of the adhesive. The tank 41 is adjustable vertically by means of slides 46 carried thereby and mounted upon a vertical rod 47, said tank being capable of being fixed in any adjusted position, by means of thumb screws 48 carried by said slide.

The well in the tank 41 is filled with adhesive from the reservoir 44, and maintained at a constant level slightly above the inturned top of the tubular portion 42. The depth of the adhesive above the tube 42 may be regulated by adjusting the tank 41 upon the rod 47, or if desired by this adjustment, the level of the adhesive may be brought below the top of this tube, to stop the application of adhesive to the wire 14.

To permit the automatic stoppage of the machine upon the exhaustion of the supply of sliver in any barrel 5, I provide an electrical make and break mechanism, fixed adjacent the bottom of the barrel, and including therein a floating member adapted to be supported by the coil of sliver, so as to gradually descend in the barrel as the sliver is withdrawn therefrom, becoming operative when substantially all of the sliver has been withdrawn.

This automatic stop mechanism, in the form of the invention shown, comprises a weight 48 connected by the pull cord or chain 49 passing over and about the pulleys 50-51, with the hand lever 36. This weight is normally held in its inoperative position by a latch mechanism 52 adapted to be released by an electromagnet 53.

Carried by, and insulated from, the cross frame 3, are two terminal rings 54-55, one of which is electrically connected with said magnet and the other of which is electrically

connected with one terminal of any desired source of power, the other terminal of which is connected with the magnet 53.

The top frame 8 carries two brushes 56-57 co-operating with the rings 54-55 respectively. One of said brushes is electrically connected with the metallic bottom 58 of each barrel 5, and the other brush is electrically connected by a wire 60 with a metallic ring 59 about and within each barrel 5, the ring 59 being spaced away, and insulated, from the bottom 58. Loosely mounted within each barrel 5 is a floating metallic ring 61, having a contact roller or rollers 62 projecting above same, so as to span the gap between the bottom 58 and ring 59 and thus close the circuit to the magnet 53 when the ring 61 reaches the bottom of the barrel. If desired, the brush 57 may be electrically connected with the top frame 8, since the bottom of each barrel rests upon the metallic platform 4, and the standards 7 will act as conductors. This however, is merely a detail within the province of the ordinary skilled electrician.

The operation of the herein described machine is substantially as follows:

When starting a machine, the wire 14 is threaded about the pulley 15, through the arbors 6 and 9 and dies 11 and 10, and about the sheave 13, and connected with the rewind mechanism, in the usual manner, the wire being passed through the tube 42 between the pulley 15 and arbor 6. After the end of the wire has been passed through said tube 42, the tank 41 is lowered so that the top of the said tube will be slightly below the level of the adhesive in the reservoir 44, thus bringing the level of the adhesive in the trough about said tube, above the top of the tube. With the subsequent feeding movement of the wire, it will pass through a shallow bath of the adhesive, and succeeding portions thereof will be successively brought into engagement with this small volume of adhesive, the adhesive being applied to the outside of the wire while it is travelling vertically at a fairly high speed. As a consequence, only a thin film of the adhesive will be applied to the wire, since there will be an insufficient interval during which the wire is in contact with the adhesive, for a portion of the adhesive to set, and thus accumulate upon the wire a substantial quantity of the adhesive sufficient to retard the subsequent setting of all of the adhesive carried by the wire, to a degree where it will become sufficiently tacky to ensure the rapid bonding of the sliver 16 thereto at the point of application of said sliver. If the wire in its rapid travel, should take up more than enough adhesive to form the desired thin film, the surplus will flow downwardly about the wire and thus be so distributed

before reaching the point of application of

the sliver to the wire as to avoid the presence at this point of a sufficient volume of the adhesive to cause its absorption by the sliver to exhaust any substantial part of the absorption properties of the sliver, or prevent the desired partial set of the adhesive to impart to it the desired tackiness. If it be found that too much adhesive is being delivered, the tank 41 may be raised 10 slightly, thus decreasing the volume of adhesive through which the wire must pass.

As adhesive is removed from the tank 41 by the wire, the supply of such adhesive in said tank will be renewed from the reservoir 44, which in turn will receive adhesive from the carboy or other container 45, thus maintaining a constant level in said reservoir and said tank.

The means described for applying the adhesive to the wire is especially adapted for use with a cold, fairly liquid, adhesive, and its use avoids the necessity for providing scrapers, or rubbers acting upon the wire, to remove surplus adhesive therefrom. Such devices are highly undesirable, as they rapidly foul and have a tendency to clean the wire, but if not used there is always present the likelihood of too much adhesive, with its resultant effect upon the absorption 25 properties of the sliver, and in the uniformity in the bond between the sliver and the wire.

When starting the machine under power, the hand lever 36 is moved to the left, thus actuating the brake slides 37 to disengage their shoes from the platform 4, and setting the clutch 35 so as to apply power to the shaft 24. With the rotation of this shaft, the platform 4 is rapidly rotated through the gear train 26 including the gear 25, and the feed sheave 13 is rotated so as to impart the desired lineal traverse to the wire 14, through the mechanism 27. At the same time power is applied through the shaft 12 30 and the pulleys 28-29, gears 30 and 31, and chain and sprocket mechanism 31, to the rewind shaft 33, and the traverse mechanism respectively.

As the wire passes axially of the platform 4, the rotation of the said platform will result in the winding of the various strands of sliver spirally about same, the rate of feed of the wire being synchronized with the speed of rotation of said platform 55 so as to regulate the pitch of the sliver.

The sliver is applied to the wire, below the die 11, which with the travel of the covered wire therethrough gives an initial compaction to the sliver before it passes through the compacting die 10 and has the binding cords or strands from the spools upon the spindles 18 applied thereto.

The first layer of sliver applied to the wire, is substantially instantly bonded thereto, by its engagement with the tacky

adhesive upon the wire, thus being held firmly in position upon the wire during its compaction thereon. Succeeding layers of sliver are wound upon this inner layer.

When the supply of sliver in any barrel 5 becomes exhausted, it is necessary to immediately stop the machine, remove the barrel and replace it by another barrel containing a fresh supply of sliver. If this is not done there may be a considerable length of wire wherein the insulating material will be thinner than in properly covered portions of the wire. Since one operator ordinarily has charge of a number of covering machines, there is always likelihood of the exhaustion of the sliver going unnoticed, thus necessitating hand refinishing of this length of improperly covered wire. The automatic stop mechanism above described avoids possibility of the machine continuing its covering operation slightly before the end of any strip of sliver reaches the wire.

As each barrel 5 is mounted upon the platform 4, the operator will make the electrical connections necessary to include it in circuit with the magnet 53. A ring 61 is then placed upon the coil of sliver, the end of the strip of sliver being passed through the ring. Thereafter as the sliver is withdrawn, the ring, which is rounded on the bottom and hollowed to make it sufficiently light, so as not to interfere with such withdrawal, will descend in the barrel, until with the movement of the last coil of sliver, it will contact with the metal bottom 58 of the container, with one or more of the rollers 62 in electrical contact with the ring 59, thus closing the circuit to said magnet 53.

As said magnet is energized, it will release the latch mechanism 52, permitting the weight 48 to drop, thus through the pull cord 49 moving the lever 36 to the left and disconnecting the clutch 35 with the resultant stoppage of the machine.

A stop mechanism such as I have described, is particularly adapted to high speed machines, since the exhaustion of the sliver in any barrel cannot be readily detected by an operator, particularly if he has a number of such machines under his control.

By using the carboy 45 for supplying the reservoir 44 with the adhesive, I secure a hydrostatic device maintaining a constant level of the adhesive in said reservoir, and at the same time am enabled to determine when the supply of adhesive is becoming exhausted, which would result in a loss of the constant level, since said carboy serves as a sight gauge for this purpose.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:

1. A wire covering machine embodying therein a rotatable horizontal platform adapted to receive a container or containers for cotton sliver, or other material, means feeding a wire axially of said platform, means applying adhesive to said wire before the sliver, or other material, is applied thereto, actuating means for said platform and said wire, feeding means, and means controlled by said magnet, and operatively connected with said actuating means, whereby, with the closing of said circuit, said actuating means will be made inoperative.

5 10 15 20 25 30

2. A wire covering machine embodying therein a fixed frame, a horizontal platform structure rotatably mounted in said frame, a container having an electroconductive bottom, and a ring of electroconductive material adjacent, and insulated from, said bottom, a movable electroconductive ring adapted to be sustained by the coil of sliver within a container and to descend therein as the sliver is withdrawn therefrom, said ring being adapted to electrically connect said bottom and said ring when the sliver is substantially exhausted, contact rings and co-operating brushes carried by said frame and said platform structure respectively, and in electrical connection with the bottom 35 of, and with the contact ring carried by, a container, respectively, an electromagnet included in circuit with said bottom and said ring, means feeding a wire axially of said platform, means applying adhesive to 40 said wire before the sliver, or other material, is applied thereto, actuating means for said platform and said wire, feeding means, and means controlled by said magnet, and operatively connected with said actuating means, whereby, with the closing of said circuit, said actuating means will be made inoperative.

ring, means feeding a wire axially of said 45 platform, means applying adhesive to said wire before the sliver, or other material, is applied thereto, actuating means for said platform and said wire, feeding means, and means controlled by said magnet, and operatively connected with said actuating means, whereby, with the closing of said circuit, said actuating means will be made inoperative.

3. A wire covering machine embodying 50 55 60 65 70 75 80 85

therein a fixed frame, a horizontal platform structure rotatably mounted in said frame, a container having an electroconductive bottom, and a ring of electroconductive material adjacent, and insulated from, said bottom, a movable electroconductive ring adapted to be sustained by the coil of sliver within a container and to descend therein as the sliver is withdrawn therefrom, said ring being adapted to electrically connect said bottom and said ring when the sliver is substantially exhausted, contact rings and co-operating brushes carried by said frame and said platform structure respectively, and in electrical connection with the bottom of, and with the contact ring carried by, a container, respectively, an electromagnet included in circuit with said bottom and said ring, means feeding a wire axially of said platform, means applying adhesive to said wire before the sliver, or other material, is applied thereto, actuating means for said platform and said wire, feeding means, and means controlled by said magnet, and operatively connected with said actuating means, whereby, with the closing of said circuit, said actuating means will be made inoperative.

In witness whereof I have hereunto affixed my signature, this 26th day of November, 1918.

WILLIAM E. COOK.
